UNITED STATES PATENT OFFICE.

MARY E. ROSS, OF BAKER, OREGON.

KNITTING-NEEDLE.

1,384,349.

Specification of Letters Patent. Patented July 12, 1921.

Application filed January 29, 1920. Serial No. 354,838.

To all whom it may concern:

Be it known that I, MARY E. Ross, a citizen of the United States, residing at Baker, in the county of Baker and State of Oregon, have invented certain new and useful Improvements in Knitting-Needles, of which the following is a specification.

This invention relates to improvements in knitting needles and has as one of its objects to provide a knitting needle having a working end so shaped and formed as to adapt the needle to be expeditiously employed in knitting and to insure of gripping of the yarn or thread when the needle is drawn in one position and to insure of free passage of the needle when drawn in another position and, in the latter instance, without likelihood of the needle catching the yarn or thread.

Another object of the invention is to so form the needle that a set of several of them may be readily employed in continuously knitting around a relatively large garment in producing the same thus obviating the necessity of resorting to purling and permitting of the garment being knitted in a more expeditious manner.

A further object of the invention is to so form the needle that while a set of several of them may be employed as stated above, a pair of the needles may on the other hand be employed in knitting other articles by the use of an attachment which may be readily applied to and removed from either needle and which when in place will prevent the knit material slipping off of the needle.

In the accompanying drawings:

Figure 1 is a perspective view of one of the needles embodying the present invention with the attachment above referred to applied thereto;

Fig. 2 is a detail longitudinal sectional view through one working end of the needle;

Fig. 3 is a view in elevation looking at the notched side of this end of the needle;

Fig. 4 is a side elevation of one working end of the needle, the view illustrating in section the attachment heretofore referred to applied to the said needle;

Fig. 5 is a view similar to Fig. 3 looking at the opposite side of the needle;

Fig. 6 is a horizontal sectional view on the line 6—6 of Fig. 4 showing the stop attachment in plan;

Fig. 7 is a perspective view of the stop attachment removed from the needle.

In the drawings the needle is illustrated as comprising a shank or body which is indicated by the numeral 1 and which in the illustrated embodiment of the invention is so formed that each of its ends will constitute a working end although it will be understood that one end only of the needle may be so formed if desired. Furthermore, inasmuch as the two ends of the needle, where both ends are working ends, are identical in form, a description of one end will suffice for both. The needle at its working end is tapered to provide a substantially conoidal terminal which is indicated by the numeral 2, this terminal being comparatively short and extending from about the dotted line a a in the drawings to the extremity of the needle. Inwardly of this terminal the needle is preferably of uniform diameter and is circular in cross section and throughout its length is free from projections or obstructions. Inwardly of the base line a a of the conoidal terminal of the needle, the working end of the needle is formed with a notch which is indicated by the numeral 3, and this notch is formed transversely in one side of the needle and consequently has two walls one of which is indicated by the numeral 4 and the other by the numeral 5. This wall 4 of the notch which may be considered as the end wall thereof is located immediately inwardly of the base line a a and is located in a plane nearly at right angles to the longitudinal axis of the shank of the needle being, however, slightly inclined at an angle to the axis and in the direction of the adjacent extremity of the needle. The notch 3 is of maximum depth at its end which is defined by the wall 4 and the depth of the notch preferably does not exceed one half of the diameter of the shank of the needle so that the notch lies practically wholly within the bounds of that side of the needle in which it is formed with the result that the depth of the notch is less than the maximum width of the notch. The wall 5 of the notch which may be considered as the bottom wall thereof is inclined gradually from the base of the end wall 4 of the notch to the circumferential surface of the needle at that side in which the notch is formed, this wall being preferably slightly curved or concaved in the manner illustrated in Figs. 2 and 3 of the drawings although it may be straight if found desirable. This wall, of course, is of

maximum width at the line where it forms a juncture with the wall 4 of the notch but at no point is it of greater width than the diameter of the needle shank and consequently 5 its side-edges lie wholly within the bounds of the circumferential surface of the shank as clearly shown in Figs. 2, 3, 4 and 5 of the drawings and as shown also in Fig. 6 of the drawings. Likewise it will be observed by 10 reference to these figures that the edge of the wall 4 of the notch lies wholly within the bounds of the circumferential surface of the needle shank so that while the formation of this notch provides a hook adapting the 15 needle to catch the thread or yarn when the needle is intentionally held in position to present its notched side to a loop of the material, when the needle is turned over so that its opposite side is presented to the loop in 20 the material, it may readily slip through the loop without catching in the material. In order to further insure against catching of the hook of the needle in the yarn or thread when it is desired to draw the needle freely 25 through a loop of the material, the lateral edges of the wall 5 of the notch 3 are beveled as indicated by the numeral 6, as clearly shown in Figs. 3, 4 and 6 of the drawings.

As heretofore stated, the invention 30 temlates the provision of an attachment for application to one working end of the needle which attachment is in the nature of a stop member and serves to prevent the goods slipping off from the needle during the knitting operation. This attachment is clearly illustrated in Fig. 7 of the drawings and the manner of its application to the needle is clearly shown in Figs. 4 and 6 of the drawings. The said attachment comprises a disk 35 40 7 which may be of rubber or any other suitable material or a combination of materials and which is preferably circular in outline and of a diameter somewhat greater than that of the shank of the needle. The said disk is formed substantially circularly with 45 an opening 8 having oppositely located side walls 9 and 10 and end walls 11. This opening corresponds to the cross sectional shape of the working end of the needle at the line 50 of juncture of the walls 4 and 5 of the notch 3 as will be evident by reference to Fig. 6 of the drawings. The disk 7 is to be applied by inserting the working end of the needle through the opening 8 until the disk occupies 55 the position shown in Figs. 4 and 6 of the drawings and it will be evident by reference to these figures that the wall 9 of the said opening engages against the bottom wall 5 of the notch 3 at its juncture with the

wall 4, the end walls 11 engaging the bevels 6 60 and the arcuate side wall 10 of the opening engaging the back of the working end of the needle. It will, furthermore, be observed by reference to Figs. 6 and 7 of the drawings that the wall 9 of the opening 8 is located 65 diametrically of axis of the disk so that the opening is located wholly at one side of the said axis. By thus locating the opening, the disk when applied to the working end of the needle will have its periphery concentric to 70 the axis of the shank of the needle. It will be understood, of course, that the disk 7 is to be of some elastic or semi-elastic material so as to adapt it to be drawn or fitted over the working end of the needle and so that when 75 applied as heretofore stated, it will lie immediately inwardly of and rest at one face against the wall 4 of the notch 3 as shown in Figs. 4 and 6 and thus be held against accidental displacement or loss. 80

Having thus described the invention, what is claimed as new is:

1. A knitting needle having a working end formed with a notch to provide a shoulder, and a stop member removably fitted 85 onto the said end of the needle and seating against the said shoulder.

2. A knitting needle having a working end formed with a notch providing a shoulder and an elastic stop member removably 90 frictionally fitted onto the said end and seating behind the said shoulder.

3. A knitting needle formed with a notch in its working end, and a stop member removably fitted onto the needle and engaging 95 in the said notch.

4. A knitting needle formed with a notch in its working end, and a stop member removably fitted onto the needle and engaging 100 in the said notch, the stop member being of elastic material and having an opening of a shape corresponding substantially to the cross sectional shape of the needle at the point of location of the said notch.

5. A knitting needle having a round shank 105 provided at its working end with a substantially conoidal terminal and formed in one side inwardly of the terminal with a notch of a depth not greater than the radius of the shank and of a width not greater than the 110 diameter of the shank, the wall of the notch next adjacent the terminal of the needle shank being inclined from the bottom of the notch in the direction of the said terminal, this and the bottom wall of the notch forming an angle of not less than ninety degrees. 115

In testimony whereof I affix my signature.
MARY E. ROSS. [L.S.]
